United States Patent Office

Des. 181,715
Patented Dec. 17, 1957

181,715

DECANTER

Ernest L. Du Pree, Weston, Conn., and James Rosati,
New York, N. Y., assignors to Schenley Industries,
Inc., New York, N. Y., a corporation of Delaware

Application October 31, 1956, Serial No. 43,617

Term of patent 14 years

(Cl. D58—8)

Figure 1 is an elevational view of a decanter showing our new design;

Figure 2 is a similar view of the decanter taken 120° to the right of Figure 1;

Figure 3 is a similar view taken 120° to the right of Figure 2;

Figure 4 is a top plan view of the decanter with the ornamental elements, as shown in Figures 1, 2 and 3, omitted for convenience of illustration, and

Figure 5 is a fragmentary sectional view as seen on the line 5-5 of Figure 3.

We claim:

The ornamental design for a decanter, as shown.
